UNITED STATES PATENT OFFICE.

EDWARD A. SMITH, OF NEW YORK, N. Y., ASSIGNOR TO OTIS ELEVATOR COMPANY, A CORPORATION OF NEW JERSEY.

SAFETY DEVICE FOR ELEVATORS.

1,132,744.

Specification of Letters Patent. Patented Mar. 23, 1915.

Application filed February 6, 1905. Serial No. 244,264.

To all whom it may concern:

Be it known that I, EDWARD A. SMITH, a citizen of the United States, residing at New York city, in the county of New York and State of New York, have invented certain new and useful Improvements in Safety Devices for Elevators, of which the following is a specification.

My invention relates to a safety device for elevators and its object is to improve upon structures of this kind now in use and to provide a device for quickly and positively clamping an elevator car to the guides over which it is adapted to run.

I will describe my invention in the following specification and point out the novel features thereof in claims.

Referring to the drawings, Figure 1 is a diagrammatic view in elevation of an elevator car and certain connected apparatus which is used in carrying out my invention. Fig. 2 is a plan view, partly in section, of my safety device, showing sections of the guides which it is intended to clamp. Fig. 3 is a plan view of a modification of my device. Figs. 4 and 5 show two other modifications of my invention. Fig. 6 is an enlarged perspective view of the wedge-shaped cams shown in Figs. 2, 4 and 5.

Like characters of reference designate corresponding parts in all of the figures.

10 designates an elevator car to the bottom of which my device is attached.

11 is a hoisting rope for the car.

12 is a governor rope connected to run with the car. This governor rope runs under a sheave 13 situated near one end of the car's travel. It may be weighted, as at 15, and pawls 16, 16 may be provided if desired and adapted to engage with ratchets in the sides of the weight to prevent its upward movement. The governor rope 12 runs over another sheave 14 near the other end of the car's travel, which is connected to a governor or speed regulator 17 by suitable gearing 18. The speed governor is arranged to actuate a gripping device 19 which grips and positively locks the governor rope when the car runs in excess of normal speed. It may be arranged to operate when the car is running in either direction. The governor rope is yieldingly connected to the car at 12' and is so arranged that when the governor rope 12 is stopped

and the car continues to move it will pull 55 loose from the yielding connection. This will cause the rope 12^A which is attached to the governor rope 12 to be pulled through the pulleys 12^B, 12^B and to be unwound from a drum 31 on the safety device and thereby 60 impart a rotary motion to the winding drum 31. It is sometimes desirable to rotate the winding drum 31 by hand from the car, and for this purpose I provide another rope 12^C on the winding drum and attach to this rope 65 a handle 12^D within reach of the operator in the car.

I will now refer to Fig. 2 and describe the clamping device or safety device for the elevator car which is there illustrated. The 70 winding drum is rotatably mounted upon hubs 35, 35 on rigid brackets 34, 34. The drum may be grooved as shown at 32 for the reception of the rope 12^A, and separate grooves 33 may be added if desired for the 75 reception of the rope 12^C. The inside of the drum is bored out to receive two shafts 36, 36, the outer ends of which are threaded one with a left hand thread and the other with a right hand thread. Feathers 36', 36' are 80 provided which engage with the drum and the shafts, so that the shafts will turn with the drum but are at the same time free to move longitudinally. The threaded ends of these shafts, one of which 37 is shown in the 85 drawing, run through collars 38, 38 which are threaded on the inside to fit the threads on the shafts 36. The collars 38 are also threaded on the outside with right and left hand threads respectively of higher pitch 90 which fit into similar threads in the rigid brackets 34, 34. Thus the collars 38, 38 form differential screws each having a high pitch thread and a low pitch thread.

Wherever I use the expression "high and 95 low pitch threads" in the specification and claims, I mean that the pitch of one of the threads is comparatively higher or steeper than the pitch of the other thread. I prefer to make the high pitch thread on the 100 outside of the collars 38, 38 of substantially the shape shown in the drawings, with a short, steep side and a long, sloping side for reasons which will be pointed out later. Near the ends of the shafts 36, 36, collars are 105 provided as shown at 39. Wedge-shaped cams 25, 25 are arranged to be moved by the collars 38 and the shafts 36 between anti-

friction rollers 24, 24. These rollers are on the ends of the jaws 21, 21 of a clamping device. The jaws 21, 21 are pivoted at 23 and are arranged to be moved into engagement with the guides 22, 22 over which the elevator is adapted to run.

I have already pointed out the manner in which the governor and its connected parts operate to cause the winding drum to be rotated. I will now describe the further operation of my safety device. When the winding drum is rotated, it will cause the shafts 36, 36 to be rotated. The collars 38, 38 will then turn in the brackets 34, 34 because their frictional resistance is less than that of the threads 37 on the inside of the collars. These by reason of their high pitch will cause the cams 25, 25 to be quickly pushed apart and between the rollers 24, 24 until the jaws 21, 21 are brought into contact with the guides 22, 22. The further movement of the sleeves 38, 38 will then be resisted by the back pressure on the cams 25 and they will move no farther, but the continued movement of the shafts 36 will now push the low pitch threads 37 through the collars and they will continue to move the cams 25, 25 between the rollers 24, 24 at less speed but with greater power and so cause the clamping device to be tightened firmly on the guides 22, 22. This will be continued until the car is brought to rest thereby, when the movement of the drum 31 will cease. The peculiar shape of the high pitch threads on the outside of the sleeves 38 will prevent the latter being pushed back by the back pressure on the cams 25, 25 because their long sloping sides will be in effect wedged into the corresponding sides of the internal threads in the brackets 34, 34. When, however, it is desired to release the clamping device from the guides, the drum 31 may be turned back by hand or otherwise, the low pitch threads will work back into the sleeves 38, 38 until the collars 39, 39 which are secured to their respective shafts abut the sleeves when they will be moved back to their original positions. If desired, springs 21^A, 21^A may be provided to move the jaws 21, 21 away from the guides when the cams 25, 25 are drawn back.

It should be noted that when the high pitch and low pitch screws are re-set so that the low pitch screws will work back into the sleeves 38, 38, until the collars 39, 39 abut the outer ends of the sleeves the high pitch screws and low pitch screws will be clamped together. That is to say, not only is the sleeve 38 held on the screw 37 by friction at the screw threads but also by friction between the collars 39 and the outer ends of the sleeves 38. The arrangement may therefore be such that when the clamping jaws meet resistance not only must the friction of the low pitch screw threads be

overcome but also the friction at the clamping connection between the collar 39 and the outer end of the sleeve 38.

In the modification shown in Fig. 3, a single high pitch and low pitch screw is shown at 38' and 37' which will work in a yoke or frame 30'. They are arranged to be actuated as in the former case by a winding drum 31' and to apply clamps 21', 21', to the guides 22, 22, in this case by means of levers 26, 26, of which said clamps form an integral part. These levers 26, 26, are pivoted together and to the frame 30' at 23', 23'.

Fig. 4 shows another modification in which instead of high pitch threads, the cam surfaces 40, 40 are attached to the drum and are arranged to co-act with similar surfaces 41, 41 on collars 42, 42, the insides of which are provided with low pitch threads 35 43, 43. In this case the shafts 36^A, 36^A should be so arranged that they cannot rotate, which is often of distinct advantage. Another advantage of this arrangement is that the friction on the low pitch threads 90 may be adjusted by means of the bolts shown at 45.

Fig. 5 shows another modification in which the high pitch screws 38^A, 38^A are inside of the winding drum 31^B and are arranged to push collars 50, 50 outward. The latter cannot rotate until projecting lugs 51 run out of engagement with fixed lugs 52. This insures the high pitch thread acting before the low pitch thread. The lugs 100 52 may be made of such length that the projecting lugs 51 will run out of engagement with them before the jaws engage with the guides.

The above description serves to illustrate 105 some of the modifications and uses of my invention. Its advantages are obvious, for with it the elevator safety device is quickly brought into operation and then the car is brought to a gradual and easy stop.

Many other modifications of my invention may be made without departing from its spirit.

I have described the clamping device as 115 on the elevator car, as that is the usual position for such devices, but it may be placed on any desired part of the elevator system, as for example on the car counterweight.

Having described my invention, what I claim is:

1. The combination of an elevator car, a clamping device therefor, guide rails co-operating with said car and device, and a differential screw having a high pitch thread and a low pitch thread for actuating the 125 clamping device, co-operating parts in engagement with said threads with different degrees of friction, the operation of said screw being controlled by the difference of friction between the high and low pitch 130

threads and coöperating parts, so that the low pitch thread is brought into operation, and the high pitch thread is held from operation by the resistance encountered when clamping device engages the guide rails.

5 2. The combination of an elevator car, a clamping device therefor, guide rails coöperating with said car and device, a high pitch screw and a low pitch screw, coöperating parts engaging said screws with different degrees of friction, said screws being arranged to actuate the clamping device and depending for their relative movement upon the difference of friction between said screws

10 and coöperating parts so that the low pitch screw is brought into operation, and the high pitch screw is held from operation by the resistance encountered when the clamping device engages the car guide rails.

15 20 3. An elevator car, a clamping device therefor, a guide rail adapted to coöperate with the said clamping device, a high pitch screw arranged to move the clamping device quickly and a low pitch screw arranged to tighten 25 the clamping device, said screws being separate and independently movable, and coöperating parts in frictional contact with said screws, the independent movement of the screws being controlled by their relative 30 friction with said coöperating parts, so that the low pitch screw is brought into operation and the high pitch screw is held from operation by the resistance encountered when the clamping device engages the guide 35 rails.

4. In a safety device for elevators, the combination of a car, a clamping device therefor, means for moving the clamping device quickly until its movement meets resistance, and additional means brought into action by such resistance for imparting a further movement to the clamping device.

45 5. In a safety device for elevators the combination of a car, a clamping device therefor, means for moving the clamping device quickly until its movement meets resistance, and additional means brought into action by such resistance for imparting a further movement to the clamping device with greater force.

55 6. The combination of a car, guides therefor, a clamping device on the car, a differential screw having a high pitch thread and a low pitch thread, coöperating parts in frictional contact with said screw, said screw being arranged to move the clamping device quickly against the guides and then to tighten it on the guides and controlled in its operation by the friction of said screw and coöperating parts, so that the low pitch thread is brought into operation and the high pitch thread is held from operation by the resistance encountered when the clamping device engages the guides.

60 85 7. In a safety device for elevators, the

combination of a car, a guide over which the car is adapted to run, a clamping device on the car, a high pitch screw arranged to move the clamping device against the guide, a low pitch screw arranged to tighten the 70 clamping device on the guide, said low pitch screw having frictional connection with the high pitch screw controlling the relative movement of the screws so that when the low pitch screw is brought into operation 75 the high pitch screw is held from operation by the frictional resistance encountered when the clamping device engages the said guide.

8. In a safety device for elevators, the 80 combination of a car, guides over which the car is adapted to run, a clamping device on the car, a high pitch screw arranged to move the clamping device against the guides, a low pitch screw arranged to 85 tighten the clamping device on the guides, parts in frictional contact with and coöperating with the high pitch screw, and means for actuating the screws by the motion of the car, the operation of said screws being 90 dependent upon the friction between one of the said screws and coöperating parts, so that when the low pitch screw is brought into operation the high pitch screw is held from operation by the resistance encountered 95 when the clamping device engages the guides.

9. In a safety device for elevators, the combination of a car, guides over which the car is adapted to run, a clamping device on 100 the car, a high pitch screw arranged to move the clamping device against the guides, a low pitch screw arranged to tighten the clamping device on the guides, parts with which one of said screws co-105 operates and is in frictional contact, means for actuating the screws by the motion of the car, and additional means for actuating the screws by hand, the operation of said screws being controlled by the 110 friction between said high pitch screw and coöperating parts, so that when the low pitch screw is brought into operation the high pitch screw is held from operation by the resistance encountered when the clamping device engages the guides. 115

10. In a safety device for elevators, the combination of a car, guides over which the car is adapted to run, a clamping device on 120 the car, a high pitch screw arranged to move the clamping device against the guides, a low pitch screw arranged to tighten the clamping device on the guides, parts coöperating with the screws and in frictional contact with one of them, and 125 means for actuating the screws by the motion of the car when the car speed reaches a predetermined limit, the operation of said screws being dependent upon the friction between one of said screws and coöperat- 130

ing parts so that when the low pitch screw is brought into operation the high pitch screw is held from operation by the resistance encountered when the clamping device engages the guides.

5. 11. The combination with an elevator car, guides over which the car is adapted to move, a clamping device on the car, a high pitch screw arranged to move the clamping device against the guides, a low pitch screw frictionally connected to said high pitch screw and arranged to tighten the clamping device on the guides, the operation of one of said screws being dependent upon the friction between said screw and coöperating parts, so that when the low pitch screw is brought into operation the high pitch screw is held from operation by the resistance encountered when the clamping device engages the guides, and a governor connected to be run by the car and arranged to actuate the screws when the speed of the car reaches a predetermined limit.

12. In an elevator safety device, the combination of a car, guides therefor, clamping devices adapted to engage with the guides, right and left hand differential screws each having a high pitch thread and a low pitch thread, arranged to operate the clamping devices, parts coöperating with said screws and in frictional engagement therewith, the operation of said screws being dependent upon the friction between said screws and coöperating parts so that the low pitch screws are brought into operation and the high pitch screws are held from operation by the resistance encountered when the clamping devices engage the guides.

13. The combination of a car, guides therefor, clamping devices adapted to engage the guides, right and left hand screws of high pitch arranged to move the clamping devices quickly against the guides, right and left hand screws of low pitch arranged to tighten the clamping devices on the guides, threaded members with which the high pitch screws are in frictional contact, and means for effecting the successive actuation of said high and low pitch screws, the successive actuation being governed by the difference of the friction between said high and low pitch screws, and the friction between the threaded members and high pitch screws, so that the low pitch screws are brought into operation and the high pitch screws are held from operation by the resistance encountered when the clamping devices engage the guides.

14. In an elevator safety device, the combination of a car, guides therefor, clamping devices adapted to engage the guides, right and left hand screws arranged to move the clamping devices quickly against the guides, right and left hand screws of low pitch arranged to tighten the clamping devices on

the guides, screw threaded members coöperating with the screws, a governor arranged to actuate the screws when the speed of the car reaches a predetermined limit, said screws being dependent upon the difference of friction between said screws and members for such operation, so that the low pitch screws are brought into operation and the high pitch screws are held from operation by the resistance encountered when the clamping devices engage the guides and means for actuating the screws by hand.

15. The combination of a car, guides therefor, clamping devices adapted to engage the guides, right and left hand screws, arranged to move the clamping devices quickly against the guides, right and left hand screws of low pitch arranged to tighten the clamping devices on the guides, screw-threaded members coöperating with the screws with different degrees of friction, said screws being dependent upon said difference of friction for such operation, so that the low pitch screws are brought into operation and the high pitch screws are held from operation by the resistance encountered when the clamping devices engage the guides and means for actuating the screws by the movement of the car.

16. In an elevator safety mechanism, the combination with hoistway rails, of friction members adapted to engage said rails, a device having portions provided with threads of the same kind or direction but of different pitch, means connecting said threaded portions to said friction members, and means for automatically rotating the said device to cause said friction members to be moved at first quickly and then more slowly by reason of difference of friction at said threads of different pitch so that the portions having low pitch threads are brought into operation and the portions having high pitch threads are held from operation by the resistance encountered when the friction members engage said rails.

17. In a safety device for elevators, the combination with hoistway rails, of friction members adapted to engage said rails, a device having differential threaded portions, means connecting said threaded portions to the said friction members, and means for automatically rotating said device to cause said friction members to be moved at first quickly and then more slowly by reason of difference of friction at said threads of different pitch so that the portions having low pitch threads are brought into operation, and the portions having high pitch threads are held from operation by the resistance encountered when the friction members engage the said hoistway rails.

18. In an elevator safety device, hoistway rails, friction members adapted to engage said rails, and a differential screw dependent

upon difference in friction at the screw threads to operate one of said members so that when the portions of said screw having low pitch threads are brought into operation the portions having high pitch threads are held from operation by the resistance encountered when the friction members engage the hoistway rails.

19. In an elevator safety device, hoistway rails, gripping jaws adapted to abut against opposite sides of said rails, and a differential screw dependent upon difference of friction at the screw threads for operating the jaws so that when the portion of the screw having low pitch threads is brought into operation the portion of the screw having high pitch threads is held from operation by the resistance encountered when the gripping jaws engage the guide rails.

20. 20. In an elevator safety device, rigid rails for the hoistway, gripping jaws adapted to be mounted on a car and engage said rails, and a differential screw to operate said jaws, said screw being dependent for its operation upon difference of friction at the screw threads so that when the portion having the low pitch threads is brought into operation the portion with the higher pitch threads is held from operation by the resistance encountered when the jaws engage the guide rails.

25 30. 21. In a safety device for elevators, the combination with hoistway rails, of gripping jaws adapted to engage said rails, positive means for operating said gripping jaws, and means for automatically increasing the pressure and decreasing the motion of said jaws when they come in contact with said rails.

40 45. 22. In a safety device for elevators, the combination with hoistway rails, of gripping jaws adapted to be mounted on the car and engage said rails, positive means for operating said gripping jaws, and means actuated by resistance of said rails to the motion of said jaws for increasing the pressure and decreasing motion of said jaws when they engage the rails.

50 23. In a safety device for elevators, the combination with hoistway rails, of gripping jaws adapted to engage said rails, a differential screw dependent upon difference

of the friction opposing the operation of said screw to operate said gripping jaws, and means for automatically operating said screw so that when the part having low pitch threads is brought into operation the part having high pitch threads is held from operation by the resistance encountered when the gripping jaws engage the hoistway rails.

24. A safety device for elevators, comprising a drum, a safety rope for turning the drum, brakes, members connected with the drum, rods for operating the brakes, said rods being connected with the members to move endwise and means dependent upon difference of friction opposing said members for first imparting a bodily endwise movement to the members and rods so as to apply the brakes quickly on rotating the drum and subsequently rotating said members in unison with the drum to impart endwise movement to the rods for actuating the brakes slowly and more powerfully, said quick operation being retarded and the slow operation effected by the resistance encountered when the brakes are applied.

25. A safety device for elevators, comprising a drum, a safety rope, the ends of which are secured to the drum, brake levers, journal bearings for the drum, members connected with the drum, rods having heads at their outer ends for operating the brake levers, said rods being carried by the members and connected therewith to move endwise, and means dependent upon difference of friction opposing said members for first imparting a bodily endwise movement to the members and rods to apply the brakes quickly on rotating the drum and subsequently rotating the said members in unison with the drum to impart endwise movement to the rods for actuating the brake levers slowly and more powerfully, said quick operation being retarded and the slower operation effected by the resistance encountered when the brakes are applied.

In witness whereof, I have hereunto signed my name in the presence of two subscribing witnesses.

EDWARD A. SMITH.
